US00D416980S

United States Patent [19]

Sato et al.

[11] Patent Number: Des. 416,980

[45] Date of Patent: ** Nov. 23, 1999

[54] **SUPPLY AND EXHAUST BLOCK FOR MANIFOLD SOLENOID VALVE**

[75] Inventors: **Hideharu Sato; Takumi Matsumoto**, both of Tsukuba-gun, Japan

[73] Assignee: **SMC Corporation**, Tokyo, Japan

[**] Term: **14 Years**

[21] Appl. No.: **29/094,743**

[22] Filed: **Oct. 9, 1998**

[30] **Foreign Application Priority Data**

Apr. 13, 1998 [JP] Japan 10-10523

[51] LOC (6) Cl. **23-01**

[52] U.S. Cl. **D23/233**

[58] Field of Search D23/233-237, D23/245; 137/596.13, 596.16, 884, 625.64

[57] **CLAIM**

The ornamental design for supply and exhaust block for manifold solenoid valve, as shown and described.

DESCRIPTION

FIG. 1 is a top, front and left side perspective view of supply and exhaust block for Manifold solenoid valve embodying our new design;

FIG. 2 is a bottom, rear and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side view thereof;

FIG. 8 is a left side view thereof; and,

FIG. 9 is a top, front and left side view thereof when in use with a manifold solenoid valve.

The manifold solenoid valve shown in broken lines in FIG. 9 is shown for illustrative purposes and forms no part of the claimed design.
